UNITED STATES PATENT OFFICE.

SAMUEL E. HITT, OF ELYRIA, OHIO, AND JOSEPH I. PEYTON, OF CHICAGO, ILLINOIS.

INGOT MOLD.

1,422,572.

Specification of Letters Patent. Patented July 11, 1922.

Application filed December 18, 1920. Serial No. 431,641.

To all whom it may concern:

Be it known that we, SAMUEL E. HITT and JOSEPH I. PEYTON, citizens of the United States, and residents, respectively, 5 of Elyria, in the county of Lorain and State of Ohio, and of Chicago, in the county of Cook and State of Illinois, have invented certain new and useful Improvements in Ingot Molds, of which the following is a 10 specification.

This invention relates to improvements in ingot molds and is for the purpose of overcoming certain difficulties encountered in the manufacture of our previous inventions claimed in United States Patents Nos. 1,139,219 and 1,139,284 issued May 11th, 1915, Canadian Patents No. 162,723 issued May 25th, 1915, and No. 162,873 issued June 1st, 1915, British Patent No. 12,047 15 (under international convention) date claimed, 22nd of August, 1914, and United States Patent No. 1,230,405 issued June 19th, 1917.

In general, the object of our invention, 20 as set forth in the above mentioned patents, is to provide an improved ingot mold adapted to minimize the defects due to pipes, blow holes, cavities and segregation usually found in ingots that have been cast 25 in metallic molds. In our present invention we accomplish this result in a similar manner to that described and claimed in the aforesaid patents by placing a vacuum chamber in the upper portion of the mold 30 walls to prevent radiation of heat in the upper portion of the mold when the ingot is being cast, thus causing the upper portion of the cast to remain liquid after the lower portion of the cast has started to 35 solidify, so that, if pipes or cavities of any kind have a tendency to form during the period of solidification, the liquid metal in the upper portion of the mold automatically feeds down and fills all such cavities as fast 40 as formed, thereby producing a solid ingot.

One object of our present invention is to provide a construction that will permit of the mold being cast with an open chamber so that the casting of the mold becomes 45 a comparatively easy matter, the chamber to be closed after the casting is made.

Another object of our invention is to provide such a construction that it can readily be made in any of the mill shops 50 with ordinary equipment.

Still another object of our invention is

to so reduce the cost of manufacture that it can be used when casting ingots which are to be rolled into shapes, such as I-beams, angles and the like, rail road rails and low 60 grade steels in general.

Referring to the drawings:—Fig. 1 is an elevation of an open top ingot mold to which our invention is applied. Fig. 2 is a vertical section on the line *y* *y* of Fig. 1, 65 showing the vacuum chamber in the upper portion of the mold. Fig. 3 is a plan view of the ingot mold shown in Fig. 1. Fig. 4 is a horizontal section on the line *x* *x* of Fig. 2. Fig. 5 is a partial section on the line *y* *y* 70 of Fig. 1 showing the upper portion of the ingot mold wall as in Fig. 2, but enlarged to show the chamber closure in more detail. Fig. 6 is a plan of the valve box. Fig. 7 is a vertical section on the line *v* *v* of Fig. 6. Fig. 8 is a vertical section on the line *w* *w* of Fig. 6.

Fig. 9 is an elevation of our ingot mold made in two sections for reasons hereinafter described. Fig. 10 is a partial vertical section on the line *z* *z* of Fig. 9. Fig. 11 is a plan view of this alternative construction.

In the drawings, 1 is the open top ingot mold, in external appearance similar to those now in common use. The lugs 2 are for the 85 purpose of stripping the mold from the ingot when, cooled, in the usual manner. 3 is the vacuum chamber in the upper portion of the ingot mold wall 4. 5 is the inner wall of the vacuum chamber 3; reinforced by the 90 vertical ribs 6 and the horizontal ribs 7. 8 is the outer wall of the vacuum chamber 3. As shown in Fig. 2, the inner chamber wall 5 and the outer chamber wall 8 are made continuous with the mold wall 4 to facilitate 95 the molding of the ingot mold 1 in the foundry.

9 is the opening at the top of the chamber 3. 10 is the closure for the top of the vacuum chamber 3, as shown in Figs. 2, 5 and 10, and 100 consists of a metallic cover resting on shoulders or shelves 11 and 12 in the side walls 5 and 8 respectively and is further secured to the side walls 5 and 8 by the welds 14 and 15 respectively. As shown in Figs. 3 and 105 11, the cover 10 is annular in form to completely cover the opening 9 between the chamber walls 5 and 8, and when welded to those walls, completely closes the vacuum chamber 3, making it air tight. The cover 110 10 is preferably welded to the chamber walls 5 and 8 by the oxy-acetylene flame, but could

be done by the electric arc or other methods now in common use.

The cover 10 is welded in between the chamber walls 5 and 8 a short distance down 5 from the top to allow room for the clay fill 16, so used to prevent damage to the cover 10 from "spill," drippings from the ladle as it passes over the molds, from one to the other, when the ingots are poured. The 10 shelves 11 and 12 are for the purpose of holding the cover 10 in place while it is being welded to the chamber walls 5 and 8 and also provides the welder with a solid background upon which to work, otherwise it would be 15 a difficult matter to prevent the fused metal from dropping through and to make a perfect weld.

As shown in Figs. 2, 4, 5 and 10, the vertical ribs 6 and the horizontal ribs 7 are integral with the chamber wall 5 and herein considered a part of wall 5. These ribs 6 and 7 are placed at intervals over the inner chamber wall 5 to prevent buckling of the wall 5 when it becomes red hot due to contact with the molten metal, when the ingot is poured. The upper extremities of the ribs 6 are beveled or cut away at 17 to be free from interference with the cover 10. A space 18 is left between the ribs 6 and 7 and 20 the outer chamber wall 8 so that the inner chamber wall 5 is free to expand both horizontally and vertically independently of the outer chamber wall 8. When the ingot is poured, the inner chamber wall 5 becomes 25 red hot, while the outer chamber wall 8 is only slightly heated, causing an expansion of the inner wall 5 greatly in excess of the expansion of the outer wall 8. If this excessive expansion of the inner wall 5 was 30 all in a vertical direction, then a flat plate could be substituted for the cover 10, but as the difference in expansion of the walls 5 and 8 is also in a horizontal direction, the cover 10 is preferably grooved to offer 35 greater flexibility, thereby relieving the welds 14 and 15 of excessive strain.

As no practical means has yet been found for welding steel and cast iron, it follows that our invention requires the mold 1 to 40 be a steel casting. For small molds, the advantages gained by the vacuum chamber would more than offset the additional cost of the steel casting. In the case of large molds, to which our invention more especially applies, the conditions are somewhat different, the molds are so heavy and so many of them are cast in a day that the expense of the steel casting for the whole mold would be considered prohibitive. Therefore, 45 for large molds, we prefer the construction shown in Figs. 9, 10 and 11, in which the mold 19 is constructed with a joint at 20, so that the lower section 21 is made of cast iron and the upper section 22, enclosing the 50 vacuum chamber 3, is made a steel casting.

By thus making the vacuum chamber 22 separate, the first cost is reduced and the life of the mold 21 becomes independent of the vacuum chamber 22. In this two section mold 19, the lugs 24 are in the same relative position as before, at the top of the full section of the mold wall 4, because the thin outer chamber wall 8 would not be strong enough to withstand the strains due to stripping. The two sections 21 and 22 are 55 fastened together by means of the flanges 25 and 26, respectively, and the bolts 27. The upper section 22, enclosing the vacuum chamber 3, is provided with lugs 28 for lifting with a crane sling or chains. 60

The outer chamber wall 8 has an opening for the exhaust pipe 29, which is welded to the wall 8 at 30 to insure an air tight joint. The pipe 29 is provided with a valve 31 or other closure, nipple 32 and cap 33, which 65 acts as an auxiliary closure and which is put on immediately after the exhaust connection has been removed. The valve 31 is protected by a hood 34, which is provided with lugs 35 that straddle the pipe 29 and 70 which sets in between the elbow 36 of the pipe 29 and the outer chamber wall 8, and is further held in place and prevented from rattling by a wire loop 37 passing around the nipple 32 and through the hole 38 in the 75 hood 34, the twisted ends 39 of the wire loop 37 being sealed at 40. By this construction of the exhaust valve 31 and the hood 34, no external lugs or projections are required to be cast on the molds 1 or 22 for the protection of the valve 31. 80

According to common practice, the inside surface 41 of the mold 1 is tapered so that the mold may be readily lifted or stripped from the ingot when cast. In mold 19, the 85 inside surfaces of the lower section 21 and the upper section 22 are tapered in a similar manner, except that the upper surface 42 is set in slightly from the lower surface 43 to make sure that the lower section 21 of the 90 mold 19 will pass the upper portion of the 95 mold 19 when stripping. 100

The operation of our invention is as follows: the ingot mold 1 or top section 22 is made with an annular chamber 3 having 110 an open top 9 and is then closed with a grooved cover 10 which is welded to the inner and outer chamber walls 5 and 8, respectively, the welds extending all the way around at 14 and 15, respectively, making 115 the chamber 3 air tight. An opening to the chamber 3 is made in the side wall 8, the exhaust pipe 29 inserted and preferably welded at 30 and the valve 31 mounted with the nipple 32. The cover 10 is then protected with the clay fill 16. A flexible pipe from an exhausting apparatus is connected to nipple 32 and the chamber 3 is exhausted to practically a perfect vacuum. After the flexible pipe is disconnected, the cap 33 is 120

placed on the nipple 32 to minimize leakage of the valve 31. The completed mold, 1 or 19, sections 21 and 22 assembled, is then placed in position and poured, until the 5 molten metal is about opposite to the grooved cover 10. The inner wall 5 of the vacuum chamber 3 soon becomes red hot, but thereafter transmits almost no heat owing to the absence of air in the chamber 3, while 10 at the same time, the lower portion of the cast loses heat fast and continuously, both to raise the temperature of the mold wall 4 and on account of the radiation due to the large mold surface exposed to the atmosphere. The result is that the upper portion of the cast remains liquid until after the main portion of the cast has solidified. During the solidification of the main portion of the cast, if any cavities start to form, 15 the liquid metal above feeds down and fills them, so that, when solidification is complete, the ingot is found to be solid and to contain the minimum percentage of piping and segregation which can be secured by hot 20 top practice. After the ingot is stripped, and the mold becomes cold, the inner wall 5 has altogether expanded and contracted 25 considerably more than the outer wall 8, both vertically and horizontally, but no damage results to the mold on account of 30 the flexibility of the grooved cover 10. It is thus seen that the general object of the solid ingot is attained by our invention embodying a vacuum chamber in the mold wall 35 and that a construction is provided which is both practical and inexpensive.

We claim:—

1. In a mold for casting ingots and the like characterized by the provision of a 40 vacuum chamber in the upper portion of the mold wall, said vacuum chamber having an outer wall and an inner wall and being provided with means connecting said inner wall with said outer wall to compensate 45 for the unequal expansion and contraction of said inner and outer walls of said vacuum chamber in both a longitudinal and a transverse direction.

2. In molds for casting ingots and the like, a mold with a closed chamber in the 50 upper portion of the mold walls from which the air is exhausted before the ingot is cast, and means for compensating the unequal expansion and contraction of the inner 55 and outer walls of the said chamber in both vertical and lateral directions, consisting of a flexible closure for the said chamber.

3. A mold having an open cavity in the 60 upper part of the mold wall, and flexible means connecting the inner and outer walls of said cavity to form a closed chamber.

4. An ingot casting mold characterized by the provision of an open cavity in the upper 65 portion of the mold wall, and means for

closing said cavity to form a chamber, said means consisting of a member sufficiently strong to withstand atmospheric pressure and sufficiently flexible to compensate for the unequal expansion and contraction of the 70 inner and outer walls of said chamber in a lateral as well as in a longitudinal direction thereby avoiding rupture of said walls and consequent loss of vacuum.

5. An ingot casting mold characterized by 75 the provision of an open cavity in the upper portion of the mold wall, a flexible member adapted to close said cavity to form a space to be used as a vacuum chamber and a refractory material covering said flexible 80 member and filling that portion of the cavity above said flexible member.

6. An ingot casting mold characterized by the provision of a relatively deep cavity in the upper portion of the mold wall, each 85 of the side walls of said cavity being integral with the wall of the mold, and a closure member adapted to be welded to each of the side walls of the cavity to form therewith a chamber, said closure member having 90 a curved cross section.

7. An ingot casting mold characterized by the provision of a continuous open cavity in the upper portion of the wall of the mold, an annular flexible member adapted to close 95 said cavity to form a closed chamber, and means for protecting said flexible member from destruction by spilled metal.

8. In an ingot casting mold having a deep open cavity in the upper portion of its wall, 100 a grooved cover welded to the walls of the cavity to form therewith a vacuum chamber, a protecting fill of refractory material entirely covering said grooved member, and a valved closure adapted to connect said 105 vacuum chamber with atmosphere or with a vacuum producing machine.

9. In an ingot casting mold, a vacuum chamber in the upper portion of the wall of the mold characterized by the provision 110 of longitudinal ribs to strengthen the inner wall of the vacuum chamber, said ribs being spaced from the outer wall chamber.

10. In an ingot casting mold, a vacuum chamber having an inner wall and an outer 115 wall characterized by the provision of a plurality of lateral stiffening ribs integral with the inner wall of the vacuum chamber and spaced slightly from the outer wall of said chamber.

11. A vacuum chamber top ingot mold characterized by the provision of longitudinal and lateral stiffening ribs on the inner wall of the vacuum chamber, said ribs extending into the vacuum chamber but 125 spaced from the outer wall thereof.

12. An ingot casting mold characterized by the provision of a vacuum chamber in the upper portion of the wall of the mold, the outer and inner walls of said vacuum 130

chamber being integral continuations of the wall of the mold and a relatively thin steel plate of curved cross section welded to each of said walls of the vacuum chamber to compensate for the relatively greater expansion of the inner wall in a lateral as well as in a longitudinal direction, thereby preventing injury to said walls.

13. In an ingot casting mold, a vacuum chamber in the upper portion of the wall of the mold the inner and outer walls of said vacuum chamber being relatively thick, and a relatively thin and curved member permanently secured to each of the rela-

tively thick walls of the vacuum chamber 15 and by its distortion compensating for the unequal expansion and contraction of said relatively thick walls, one of said relatively thick walls being provided with lateral and longitudinal stiffening ribs.
